COMBINED PRICE CALCULATOR AND MENU TICKET HOLDER

Jerry L. Gilomen, Chicago, Ill., assignor to Restaurant Technology, Inc.

Filed June 12, 1974, Ser. No. 478,447

Term of patent 14 years

Int. Cl. D19—02

U.S. Cl. D19—76

FIG. 1

FIG. 3

FIG. 1 is a top perspective view of a combined price calculator and menu ticket holder showing my new design;

FIG. 2 is a left side elevational view; and

FIG. 3 is a rear elevational view.

I claim:

The ornamental design for a combined price calculator and menu ticket holder, substantially as shown.
